Specification of Letters Patent.

Patented Jan. 26, 1915.

Continuation of application Serial No. 285,802, filed November 4, 1905. This application filed November 3, 1914. Serial No. 870,066:

To all whom it may concern:

Be it known that I, JOSEPH BECKER, a citizen of the United States, residing at Washington, in the District of Columbia, have 5 invented certain new and useful Improvements in Copying or Enlarging Cameras, of which the following is a specification.

The present application, identified for convenience of cross reference as, Case L¹, 10 is filed as a continuation of my earlier application for patent on photographic cameras, Case L, filed November 4, 1905, Serial No. 285,802; being the same in substance as such earlier application, with certain desirable additions.

My invention relates to copying or enlarging cameras of the type in which the two end frames, that is to say, the support for the object plane and the support for the image 20 receiving plane, are respectively pivoted on the diametral lines where such two planes are met by a meridional plane of the lens; this being done to permit of tilting the said two end frames toward each other to produce desired changes in the shape of the projected image.

It is well known that a negative which was inclined to the vertical during exposure in the taking camera is distorted so as to 30 show all vertical lines of buildings, etc., as converging or diverging instead of parallel, and that the parallelism of these vertical lines may be recovered by copying or reproducing from the distorted negative in a 35 copying or enlarging camera of the type referred to. The process, however, is difficult to apply so as to secure the best attainable results, because if one frame be inclined to secure parallelism, the other frame will have 40 to be inclined to recover the sharpness of focus lost in inclining the first frame, and this inclination of the second frame redenforms the image. The problem is further complicated by the fact that the relation be- 45 tween corresponding inclinations of the two end frames must change when any change is to be made in the size of the image.

One object of my invention is to provide 50 mechanism that shall compel the two pivoted end frames to tilt simultaneously toward each other in accordance with correct optical principles so that the operator need only

tilt one of the frames either directly or by means of the mechanism in order that the other frame shall simultaneously turn in the 55 manner and degree required to keep all parts of the image uniformly sharp, if the image was sharp when the end frames were parallel; and a further object of my invention is to provide end frame tilting means adapt- 60 ed to coöperate with and not interfere with the operation of automatic focusing mechanism such as disclosed, for instance, in my British Patents 24,292 of 1911 or 29,701 of 1912, in order to keep all parts of the projected image sharply in focus at all inclinations of the frames and for all extensions of 65 the camera.

In the accompanying drawings, which are made to scale in all essential particulars: 70 Figure 1 is a plan of a copying or enlarging camera provided with my tilting mechanism in its theoretically exact form, the end frames being in parallel relation and mounted to tilt on diametral axes P, P' that 75 are vertical. Fig. 2 is a similar view of the same camera with the end frames in a tilted relation. Fig. 3 is an elevation, with parts broken away for clearness, showing a simplified form of my tilting gear in combination with focusing linkage of the form shown in Figs. 7 to 12 of my said British Patent 24292/11, the end frames being mounted to tilt on diametral axes P, P' that 80 are horizontal. Fig. 4 is a diagram illustrating the geometrical principles involved 85 in Fig. 3 and generally in all forms of the invention. Fig. 5 shows a distorted negative. Fig. 6 shows its corrected and enlarged reproduction as made in the camera 90 of Fig. 3. Figs. 7 to 9 show pin hole cameras used to illustrate the principles of photographic perspective. Fig. 10 is a plan view of a combination similar to that of Fig. 3, but comprising the preferred type of focusing camera and gear shown in Figs. 17 and 95 19 to 22 of my said British Patent 24292/11, and having the diametral tilt axes P and P' vertical as in Fig. 1. Fig. 11 shows a modified form of the tilting lever of Fig. 10. 100

Theory of inclined images.—My tilting gear must necessarily act to tilt the end frames in accordance with the law governing the image formation of inclined planes,

This law may be established as follows: Let P and P', Fig. 4, be any two conjugate foci on the principal axis of the lens 99, which has its nodal points at N and N', and its principal foci at F and F' determining a focal length FN, equal N'F', equal f . The conjugate foci P and P' may have any positions determined by Newton's formula

10

$$PF \cdot F'P' = f^2 \quad (1)$$

which is given as equation 4 of my British Patent 24292/11. This equation may be written in the form

15

$$(PN - f) (P'N' - f) = f^2$$

whence

$$PN \cdot P'N' - f \cdot PN - f \cdot P'N' + f^2 = f^2$$

and

20

$$PN \cdot P'N' = f(PN + P'N').$$

Dividing both terms by the product $f \cdot PN \cdot P'N'$, we obtain

25

$$\frac{1}{f} = \frac{1}{P'N'} + \frac{1}{PN} \quad (2)$$

which is the standard lens formula for full conjugate distances PN and N'P' here directly derived from Newton's formula to

30 show that the two formulae are exact mathematical equivalents. These formulae have been followed in making the drawings, as may be verified with the aid of the scales shown on the various sheets. In Fig. 4 under consideration

35

$$NN' = 4 \text{ cm.}$$

$$FN = N'F' = f = 30 \text{ cm.}$$

40

$$PF = 20 \text{ cm.}$$

$$F'P' = 45 \text{ cm.}$$

$$PN = 50 \text{ cm.}$$

$$N'P' = 75 \text{ cm.}$$

Now let QR, Fig. 4, be an object plane which is pivoted at P and which has been inclined to meet the cardinal planes F and N of the object space in points V and T, respectively. Any rays PN, QN, RN and VN converging at the nodal point N, in the object space, will emerge in the image space 50 without change of direction; but they will all be offset so as to diverge from the nodal point N'. On the other hand, all rays PT, QT, RT, and VT, being finally merged in the one ray VT of the object space, will 55 produce the common emergent ray T'Q' which proceeds with N'J parallel to VN because V is a focal point of the principal focal plane F. This common ray T'Q' produced meets the group of rays diverging 60 from N' in the image points R', P', Q', and V'; the latter, V', being at infinity, does not appear in Fig. 4. Plane Q'P'R' is, therefore, the image of plane QPR; a fact which becomes still more evident by noting that

point T' is simply the image of point T. 65 The inclinations of these two conjugate planes QR, Q'R' out of their normal or parallel relation are measured by the angles NTP and N'T'P' or α and α' , which they form with the principal planes NT, N'T' of the lens. By inspection of Fig. 4 it is seen that

$$\tan. \alpha = \frac{NP}{NT}$$

also that

$$\tan. \alpha' = \frac{N'P'}{N'T'}$$

whence

$$\frac{\tan. \alpha'}{\tan. \alpha} = \frac{N'P'}{N'T'} \times \frac{NT}{NP} \quad 80$$

and, noting that NT equals and cancels N'T', we finally deduce

$$\frac{\tan. \alpha'}{\tan. \alpha} = \frac{N'P'}{NP} \quad (3)$$

This equation 3 is fundamental and leads to the following theorem:

The inclinations of conjugate inclined planes, as measured by the tangents of the angles of inclination, are proportional to the distances NP and N'P' of the central conjugate points P and P' from their respective nodal points N and N'.

Now let the object plane QR of Fig. 4 contain a distorted negative which is shown in Fig. 5 as it would appear to an observer looking in the direction of arrow 300, Fig. 4, and which has lines WX, QR and YZ converging in a point V situated in the principal focal plane FV of the lens in Fig. 4. Then Fig. 6 shows the enlarged sharply focused and straightened out positive 105 W'X'Y'Z' to be seen in the image plane Q'R' by looking in the direction of arrow 301, Fig. 4.

Point V, being located in the principal focal plane FV, Fig. 4, is the focus of parallel rays such as T'Q' and N'J, so that the image V' of V must be situated at lower infinity in Figs. 4 and 6 and this explains why the three lines W'X', Q'R' and X'Y' of the positive, Fig. 6, must be parallel.

The image diameter E'G', Fig. 6, that lies in the axis P' of Fig. 4, and the object diameter EG, Fig. 5, that lies in the axis P of Fig. 4, are conjugate focal lines perpendicular to the paper in Fig. 4, and their lengths (of 16 and 24 centimeters, respectively) are proportional to the conjugate distances N'P' and NP. We, therefore, have

$$\frac{E'G'}{EG} = \frac{N'P'}{NP} = n \quad (4)$$

where n designates either the value of the copying factor as measured along the tilt

axes P and P'; or, the scale of reproduction for all lines of the object when the end planes QR and Q'R' are in their normal position perpendicular to the lens axis FF'.

5 Combining the results of equations 3 and 4, we finally obtain

$$\frac{\tan. a'}{\tan. a} = \frac{N'P'}{NP} = n \quad (5)$$

10 *Tangent tilt*, Figs. 1 and 2.—The principle involved in equation 3 is embodied in my "tangent tilt," Figs. 1 and 2, where 400, 401 are the rails of a bench upon which is rigidly mounted the lens frame L carrying a lens 99, the nodal and focal points of which are, respectively, indicated by dots N, N' and F, F'. On the same bench are adapted to slide a carriage 402 and a carriage 402'. On carriage 402 is pivotally mounted the object frame O, whose vertical diametral axis of rotation is indicated by a dot P. This frame O has an arm 403 slotted perpendicularly to the frame to admit a pin p which is mounted on a bar 404 guided in 25 a dovetail groove of carriage 402 to slide transversely of the carriage 402. The image frame I is similarly mounted on carriage 402'; its vertical diametral axis of rotation being P'; its slotted arm 403'; its traversing 30 pin p'; and its traversing bar 404'. The distance PH, Fig. 2, from axis P to the path of pin p, and the distance P'H', Fig. 2, from axis P' to the path of pin p', may be of any length desired, but they should be equal 35 as shown so that the pins p and p' shall move along the tangents of arcs having the same radius.

The motions of pins p, p' and of their bars 404, 404' are controlled through pins 40 b, b' by a slotted lever 410 pivoted at c on a bar 411 which is rigidly clamped to the bench by a bolt 412 which passes freely through bar 411 and screws into an enlarged clamp nut 413.

45 The distance cK, Fig. 2, from fulcrum c to the path of pin b should equal NP; and the distance cK', Fig. 2, from fulcrum c to the path of pin b' should equal N'P'. To facilitate the determination of these distances the lever 410 is preferably graduated as shown from the fulcrum c as zero point in either direction. In Fig. 1, for instance, where cb and cb' are, respectively, equal to cK and cK' of Fig. 2, it is seen that cb and NP are both equal to 50 centimeters; while cb' and N'P' are both equal to 75 centimeters.

The three pins b, c, b' might be shifted to the right or to the left without changing 60 their tilting effect on the end frames, provided the specified equality of cK and cK' to NP and N'P' be preserved. In Fig. 1, pin b' is mounted exactly in alinement with the path of p'; as a result pin b can-

not be in alinement with its corresponding pin p, but must be offset a distance d, Fig. 1, equal to the internodal distance NN'.

To permit of making the offset d exactly equal to any given internodal space NN', the traversing bar 404 is divided into two parts 404 and 414 having feet 415 and 416 which are clamped together by screws 417. These screws 417 screw into foot 415 and pass freely through a longitudinal slot formed in foot 416. The latter is provided with an index mark or arrow head 418 to indicate the degree of offset on a scale which is graduated on foot 415. This scale runs from the zero point five spaces to the right for internodal spaces NN' that are positive; and it runs from the same zero point five spaces to the left for internodal spaces NN' that are negative. A Vernier scale might be substituted for the plain scale shown, as readily understood.

The lens shown, lens 99, has a focal length FN or N'F' of 30 centimeters and a relatively large internodal space NN' of plus 4 centimeters, the latter being selected relatively large for clearness. The exact structural conditions which are all satisfied in Figs. 1 and 2 may be summed up in the three following equations.

$$\text{Constant } d = NN' = 4 \text{ cm.} \quad (6)$$

$$\text{Variable } cK = NP = 50 \text{ cm.} \quad (7)$$

$$\text{Variable } cK' = N'P' = 75 \text{ cm.} \quad (8)$$

If the internodal space NN' of the lens to be used happens to be known, all proper adjustments can be made, without knowing the focal length of the lens, in three steps, as follows: First. Set and clamp foot 416 on foot 415 so that the arrow head 418 shall point to the known internodal space, which in the present instance is 4 cm. Secondly. Set the object frame O in focus on right infinity, and the image frame I in focus on left infinity, so that P and P' shall, respectively, coincide with the principal foci F and F' of the lens. Thirdly. Set and clamp bar 411 to bed 400, 401 so as to hold the fulcrum point c exactly midway between pins b and b'. The carriages 402 and 402' may now be separated to permit of setting the end frame axes P and P' in focus on each other and the device is ready for use.

With lever 410 held parallel to the lens axis as in Fig. 1, the end frames O, I may be moved toward and away from the lens 99 to focus for any desired scale of reproduction as freely as if the tilting mechanism were not present. Moreover, any motions of P and P' are also communicated to b and b', respectively, so that the lever arms cb and cb' are varied automatically in such manner as to remain constantly equal to the varying distances PN and P'N'.

Rocking lever 410, as in Fig. 2, therefore, moves pins p , p' through distances Hp and $H'p'$, respectively, equal to distances Kb and $K'b'$ and exactly proportional to the distances PN and $N'P'$, whatever these distances may happen to be; and, as the pins p , p' move along tangents to arcs of equal radius PH and $P'H'$, Fig. 2, the end frames are tilted exactly as required by equation 3, 10 which is observed in all relative positions of the frames, even when the axes P and P' are not in focus on each other; that is to say, even when points P and P' are not located so as to satisfy equation 1 and its 15 equivalent equation 2, but if the camera is properly focused with its end frames parallel so as to satisfy equation 1 and its equivalent equation 2, then all parts of the image will be and remain in focus when the end 20 frames are tilted by rocking the lever 410.

The focusing of the end frames in their parallel relation may be done with a ground glass in the ordinary manner, or by computation, or by a focusing scale, or preferably 25 by means of automatic focusing mechanism such as the linkage focuser of my British Patent 24292/11 or the radial cam focuser of my British Patent 29701/12.

Complete form, Fig. 3.—A complete combination of focusing and tilt gear is shown 30 in Fig. 3, where the camera proper and linkage are those illustrated in Figs. 7 to 12 of my said British Patent 24292/11, and where the tilting gear is of simpler form than that 35 of my present Fig. 1. The simplicity is secured at the cost of accuracy; but the loss in accuracy is not appreciable if the device be used within prescribed limits.

The bench 100, slideway 102, carriages 103, 40 104, pin 111, bearings 112, 113, bolts 115, 117, and the linkage ABA'D or 120, 121, 122 and 123 are all substantially as shown in Figs. 1 to 12 of my said British Patent 24292/11; but blocks 105, 108 and 109 are 45 slightly modified to provide for pivoting the end frames. To facilitate comparison with present Figs. 1 and 2 the lens used is the same lens 99 and the frames used are the same frames O, L, I shown set and tilted 50 exactly as in Fig. 2; but the frames are here identified as O', L', I'.

The object frame O' has trunnions, such as 210, by which it is mounted to swing between uprights, such as 211, which are rigidly mounted on block 108; and the image frame I' has similar trunnions 212 and uprights 213 mounted on block 109. The horizontal axes of these trunnions are indicated by dots P, P'.

60 The object frame O' has fastened thereto a bracket 214 carrying a wrist pin p which is mounted to form a crank arm Pp at right angles to the object plane in frame O'. The image frame I' has a similar bracket 216

and wrist pin p' forming a crank arm $P'p'$ 65 of the same length as Pp . These crank arms Pp and $P'p'$ are connected to turn simultaneously in opposite directions by a slotted lever 218 which is fulcrumed on the lens frame L' by means of a stud c mounted on 70 a bracket 220. This bracket is adjustably held by means of screws 221 which pass through slots of the plate 220 into the lens frame L'.

The device is adjusted for use with a 75 given lens 99 by first adjusting the linkage focuser and then by adjusting the tilting gear. By temporarily locking lever 218 in the position parallel to axis PP', the end frames O, I are held parallel, and in this 80 relation they may be separated or brought together as freely as if they were rigidly mounted on the carriages 103, 104, and not connected by tilting gear. The apparatus with its frames in such parallel relation is, therefore, first adjusted in the manner set forth in my said British Patent 24292/11, so that the Newtonian or constant product space elements DA, DA' of the linkage shall always equal the Newtonian 85 distances FP, F'P' of the lens. The carriages 103, 104 are then moved into the position where the space elements DA and DA' are equal; and finally pin c is set and clamped midway between the wrist pins p and p' . 90

By this adjustment the lever arms cp and cp' in the normal position are made equal to what they should be for a lens that has its two nodal points N and N' coincident; and they act to turn the crank arms Pp and $P'p'$ 100 through angles whose sines, proportionally represented by pS and $p'S'$, Fig. 3, vary approximately in accordance with the law laid down above for the tangents, proportionally represented by pH , $p'H'$, Fig. 2. This simplified form of tilter, Fig. 3, may, therefore, be designated as the sine tilter, whereas the theoretically correct form of Figs. 1 and 2 may be designated as the tangent tilter.

Actuating the linkage 120—123 does not 110 change the inclination of the tilt lever 218, if the tilt lever happens to lie parallel with the slideway, in which position the lever holds the end frames parallel; but if the tilt lever 218 is in inclined position the two end frames are also inclined, and at least two of these three inclinations will be changed by any actuation of the linkage 120—123, as required in view of equation 5 by the changes produced in the copying factor n . If the 120 operator, therefore, takes hold of one of the end frames and slides it along or tilts it in any manner, the focusing mechanism (which now consists in the combination of the linkage 120—123 with the tilt lever 118) 125 will simultaneously displace the other frame longitudinally and angularly in the manner and degree required to keep all points of the

image at all times sharply in focus; that is to say, the image and all parts thereof will always remain in focus, and no motion permitted by the mechanism can throw any 5 point of the image out of focus. The middle horizontal line of the image is kept in focus by the linkage 120—123 alone, but the top and bottom parts of the image are focused at all times and in all positions by the 10 coöperation of the linkage with the tilt lever.

Second complete form, Fig. 10.—The camera of Fig. 3 has the advantage of being well suited for illustrating and disclosing 15 the principles involved, but it is not the preferred practical form, because the linkage ABA' shown produces side pressures that increase friction. In the preferred form, Fig. 10, I use a camera of the type illustrated in Figs. 19 to 22 of my said British Patent 24292/11 in combination with the very smoothly working linkage shown in Fig. 17 of the same patent and the tilt axes P, P' are made vertical as in present Fig. 1. 20 The bed, in Fig. 10, comprises two parallel rails 600, 601, connected at their middle by a crossbar 602, which supports the lens pintle D at horizontal distances FD and F'D' from the principal focal planes F and 25 F' of the lens. The object frame pintle A is connected at a horizontal distance PA, equal to FD, from the vertical pivotal axis P of the object frame O⁶, by means of a rigid, but adjustable, connection comprising 30 the carriage 603, block 604, clamp bolt 605, and bracket 606. The image frame pintle A' is similarly connected at a horizontal distance P'A', equal to F'D', from the vertical pivotal axis P' of the image frame I⁶, by 35 means of a rigid, but adjustable, connection, comprising the carriage 603', block 604', clamp bolt 605' and bracket 606'. The three 40 pintles A, D, A' are connected by my preferred form of focusing linkage which is composed of two equal short links DB and 45 DB'', and of four equal long links AB, AB'', A'B and A'B''. The two short links are adjustable to permit of making their length BD equal to the square root of the 50 difference between the squares of the long link length AB and the focal length FN. The tilting gear comprises equal crank arms P_p and P'p' connected by a slotted lever 55 618, having its fulcrum c adjustably mounted on the lens frame L⁶ by bracket 620 and screws 621. The ratio P_p/FN of 60 crank arm length to the focal length is 20 to 30 in Fig. 10, and 21 to 39 in Fig. 3, so that the two tilting gears are substantially alike in every particular. The gear of Fig. 3, however, is shown as acting correctly to make the image plane meet the nodal plane N' at T' directly opposite T, as would be the case if the tangent tilter of Fig. 1 were

used; whereas, the gear of Fig. 10 is shown 65 as producing a slight offset from T' to T''. This difference is due to the fact that the camera of Fig. 3 is set for copying factor n equal 1.5, at which scale this particular sine tilter does act almost correctly; whereas, the camera of Fig. 10 is set for copying 70 factor n equal 1.2, at which scale the same gear must produce the appreciable offset T'T'' shown.

In Fig. 10, which was planned so as to 75 avoid fractional values of the scale annexed thereto, the three adjustable dimensions of the focusing gear are PA, P'A' and BD, and their values are, respectively, 41 cm., 22 cm. and 40 cm., as indicated in the equations 80 noted on the drawing close by Fig. 10. In practice these three dimensions are determined automatically, without measurement so that fractional values are as easily taken care of as any others; thus: dimension PA 85 is determined automatically by bringing A into coincidence with D and focusing the object frame O⁶ on right infinity; similarly, dimension P'A' is determined automatically by bringing A' into coincidence with D and 90 focusing the image frame I⁶ on left infinity; finally, dimension BD and its equal DB'' are determined automatically, after the determination of dimensions PA and P'A', by setting the object frame O⁶ and the image 95 frame I⁶ in focus on each other.

After the focusing mechanism has been 100 fully adjusted and regulated as just explained with the end frames in parallel relation, the focusing gear ADA' is set to make distances AD and DA' equal to each other, and then the fulcrum c of the tilt lever is set and clamped exactly half way between pins p and p', as previously explained in connection with Fig. 3. 105

The tilt lever 618 of Fig. 10 may in certain cases preferably be made as in Fig. 11, where the modified form of lever 718 has pivotal connection with the end frame pintle p and sliding connection with the other two 110 pintles c and p'. 110

Correction of distortion.—Distortion as it is usually encountered in practice is illustrated in Fig. 5, where the trapezoid WXYZ shows the negative outline obtained in photographing a rectangular wall whose ends WX and YZ were vertical in the real wall. The operator, therefore, wishes to use the negative of Fig. 5 to produce a copy such as W'X'Y'Z', Fig. 6, in which the verticals 115 W'X' and Y'Z' are parallel. To do this with the camera of Fig. 3, he mounts the negative, Fig. 5, in the object frame O' so that its middle vertical PV shall be perpendicular to the horizontal tilt axis P, and 120 then, going back to the image frame I', he tilts the frames in the direction and to the extent required to make the images of the 125

verticals WX and YZ exactly parallel. Parallelism is easily determined by means of a pair of dividers or by means of a graduated rule. When parallelism is secured, it 5 will be found, as already proved above, that the vanishing point V has been brought into the nearer principal focal plane F , as shown in Figs. 3 and 4, such focal plane being considered as extending all the way to 10 infinity if necessary to make the rule general. Thus the perpendicular distance FV is and should be infinite when the verticals WX , YZ of the negative are parallel.

Correct perspective.—In the majority of 15 cases parallelism of the verticals is all that the operator desires. By mounting the negative in frame O , however, to make the vertical distance FV either longer or shorter than shown in Figs. 3 and 4, and the angle 20 a correspondingly smaller or larger, the operator can secure differences in the relative length of the rectangular image, Fig. 6. In Fig. 6 the length $W'X'$ shown is 30 cm. and the width $X'Z'$ is 24 cm. so that the relative 25 length or ratio of length to width is $30/24$, or $5/4$. It is this ratio that can thus be varied, and only one of the different reproducible proportions of the rectangular image will correspond to the correct perspective 30 that would have been obtained if the negative had been held exactly vertical during the exposure. I have discovered the novel principle that this correct perspective is obtained when the distance NV or h'' , Fig. 4, 35 has a certain value, as will presently be explained with the aid of the pin hole cameras shown in Figs. 7 and 8.

Questions of photographic perspective are 40 most easily treated by means of pin hole cameras because the pin hole of such cameras may be considered as a lens that is perfectly rectilinear and always in focus, and that has its two nodal points N and N' coincident in one point as single center of perspective. 45 In glass lenses the nodal points hardly ever coincide, but the same perspective principles apply, because the internodal space of the lens simply produces a relative shift or translation of the object and image 50 spaces, or of the incident and emergent parts of the diagram without introducing any changes in direction, shape or size.

In Fig. 7, 500 is a common pin hole camera with its pin hole at M and showing 55 how the camera was held during exposure to produce a negative 501 of a small vertical wall 502, the axis PM of the camera being aimed directly at the central point P^s of the wall. The height of this wall 502 is 80 cm. 60 and the unseen uniform width is supposed to be 64 cm., so that its height is $80/64$, or five-fourths ($5/4$) of the width. According to the known rules of perspective, the negative 501 will show all verticals of the wall

as vanishing in the point V (Fig. 7) where 65 the produced plane of the sensitized surface on plate 501 is met by the vertical or plumb line MV drawn through the pin hole M . The exact outline of the distorted picture obtained is shown in Fig. 5, where the horizontal diameter EPG is 16 cm. long. If a tilt back had been used to turn the plate on the horizontal axis P into the vertical dotted position 503, the picture qPr thus obtained would be free from distortion; that is to 70 say, it would be rectangular, 16 cm. wide and $5/4$ of 16, or 20 cm. high. This correct negative is a vertical section of the rays emerging from the pin hole M . Any other vertical section $Q'P'R'$, Fig. 7, of the incidental parts of the same rays through M produces a correct perspective such as desired in making the copy or enlargement shown in Fig. 6, where the width $E'G'$ is 24 cm. and the height $Q'R'$ is $5/4$ of 24, or 85 30 cm.

Now let the distorted negative 501 be set and held in front of an enlarging pin hole camera 510, Fig. 8, at any distance and in any desired position, but so that its vanishing point V shall be situated somewhere on the arc 513 of a circle drawn about the pin hole M' as center with a radius $M'V$ or h' equal to the vertical distance MV , or h , in the taking camera, Fig. 7; and let a screen 90 511, Fig. 8, be set and held in any desired position 511 or 512 inside of the camera 510, but parallel to the radius h' , then the projected image $Q'P'R'$ or $Q'''P'''R'''$ so obtained will be similar to the correct perspective $Q'P'R'$ of Fig. 7, as will now be proved.

Any correct perspective $Q'P'R'$ in Fig. 7 is evidently similar to the correct vertical negative qPr , and the height qr of this negative is twice the height of the linear element Pr . The similar triangles PrR and VMR yield

$$Pr = h \times \frac{RP}{RV} \quad (9)$$

110

All images such as $Q'P'R'$ and $Q'''P'''R'''$ obtained in Fig. 8 are evidently similar to each other and to the perspective $q'Pr'$ that is obtained by drawing a plane $q'r'$ through 115 P parallel to the radius h' . The horizontal diameter P of this image $q'r'$, Fig. 8, is identical with the common horizontal diameter P of images qr and QR in Fig. 7, and this, in view of Fig. 5, is 16 cm. long.

In Fig. 8, the pin hole M' and all lines of the negative 501, converging in V , determine planes intersecting on the vertical line h' , and, therefore, these planes must meet the plane $q'r'$, which is parallel to h' , along 125 lines that are parallel so that the image $q'r'$ has all of its horizontal diameters equal, or 16 cm. long.

The similar triangles $Pr'R$ and $VM'R$ yield

$$Pr' = h' \times \frac{RP}{RV} \quad (10)$$

5

Dividing equation 9, term for term by equation 10, we obtain

$$Pr' = \frac{h \cdot RP}{RV} \times \frac{RV}{h' \cdot RP} = \frac{h}{h'} \quad (10)$$

10 or

$$Pr' = Pr \times \frac{h'}{h} \quad (11)$$

15

As h' of Fig. 8, however, was made exactly equal to h of Fig. 7, this equation 11 yields

$$Pr' = Pr = 10 \text{ cm.}$$

20

It could similarly be shown that any other corresponding height elements in Fig. 7 and Fig. 8 are equal, and that the image $q'r'$ of Fig. 8 is in all respects the exact duplicate of the 16 by 20 centimeter image qr of Fig. 7, although the angle PVM' of Fig. 8 is very different from the corresponding angle PVM or i of Fig. 7. The relative height $Q'R'/E'G'$ obtained in the final image, Fig. 6, is, therefore, simply proportional to the length h' , Fig. 8, or h'' , Fig. 4, and this principle is entirely independent of differences that may exist between the focal length of the lens in the taking camera, Fig. 7, and the focal length of the lens in the copying or enlarging camera, Fig. 4.

25

The distance h in the taking camera may be calculated by noting that h is the hypotenuse of the right angled triangle VPM , in which the two sides VP and PM are easily measured, PM being the depth of the camera during exposure, and VP the directly measurable distance from the central point P of the negative to the vanishing point V .

30

The angle PVM or i in Fig. 7 is equal to the inclination of the taking camera 500 during exposure, so that if this inclination has been noted we can, after simply measuring PV on the finished negative, calculate

35

$$h = PV \cdot \sec. i \quad (12)$$

40

The distance h'' in Fig. 4 is necessarily longer than the focal length FN of the lens 99 so that correct perspective can only be recovered by using a reproducing lens 99 whose focal length is shorter than the vertical distance h in Fig. 7.

45

The above exposition leads to the three following simple rules, which are all that the practical operator need remember.

Rule 1: To recover parallelism of verticals converging in a point V of the negative, in-

cline the negative so as to bring V into the 65 nearer focal plane of the lens.

Rule 2: To recover correct perspective, as well as parallelism, follow Rule 1, shifting the negative to increase or decrease the vertical distance VF , Fig. 4, so as to make the 70 inclined distance h'' in the enlarging camera, Fig. 4, equal to what the vertical distance h was in the taking camera, Fig. 7.

Rule 3: A reproducing lens having a focal length equal to or greater than h in 75 Fig. 7 cannot be used to recover correct perspective, but it will still answer to secure parallelism of the verticals under Rule 1.

Short focus taking and reproducing lens.—Where the focal length of the taking lens 80 M , Fig. 7, is so short that variations in the depth PM of the camera due to focusing are nil or negligible as in the smaller so-called "fixed focus" hand cameras, there is a special advantage in using the same lens 85 as reproducing lens in the copying or enlarging camera, because the focal length FN , Fig. 4, and the depth PM , Fig. 7, then are and remain equal, and correct perspective is obtained when the triangle VFN of 90 Fig. 4 is made exactly equal to the triangle VPM of Fig. 7. Angle i of Fig. 7 and angle a'' of Fig. 4 are then equal to each other and to the inclination a' of the image frame I, Fig. 4. As the line VP of the 95 negative, Fig. 7, is then equal to the vertical VF in the enlarger, Fig. 3, it must be shorter than the hypotenuse VP , Fig. 3; and, therefore, the center P of the negative must be shifted in plane PT , Fig. 3, toward T 100 through the hypotenuse excess ($VP - VF$), Fig. 3, to bring the vanishing point V of the negative into coincidence with V of Fig. 3. Where the copying factor n is large, as usual with small negatives, the distance PF , 105 Fig. 3, is relatively short and the shift or hypotenuse excess ($VP - VF$), Fig. 3, is so small as to become negligible. If, therefore, we neglect the slight shift required in practice, from P toward T , Fig. 3, to bring 110 the vanishing point of the negative, under Rule 1, into the focal plane F in exact coincidence with V , all rules for securing a sufficiently correct image are reduced to the following simple

Rule 4: To secure a practically correct perspective, where the taking lens is of short focal length and is used as enlarging lens, set the image frame I of the enlarger to make its inclination a' , Fig. 3, equal to 120 the inclination i of the taking camera, Fig. 7.

A small hand camera with automatic means for recording its inclination directly on the negative at the moment of exposure is, therefore, the natural complement of my 125 present invention.

Indirect advantages.—My invention has several indirect advantages that are prob-

ably of greater value and importance than its direct advantage. The direct advantage of the invention is that it permits of taking a distorted negative to make therefrom, very 5 easily, positives, or even other negatives, of any desired size and showing no trace of distortion. Distorted negatives in present practice, however, are only produced in the rare instances where their production is un- 10 avoidable, as where the swing back and rising front of the taking camera have reached the limits of their adjustments and would have to be moved farther to secure full cor- rection.

15 The operator who has a copying or enlarging camera with combined tilt and focusing gear such as shown in Fig. 3 corrects distortion so easily at any desired scale of reproduction that he need never 20 make any efforts to avoid it. With him distortion will be the rule instead of the exception, because distorted negatives are more easily produced and are better in all other respects than correct negatives made under 25 the same conditions with rising front or swing back. Suppression of the rising front and of the swing back and of the level, and of the trouble involved in the use of such devices not only simplifies the construction 30 and manipulation of the taking camera, but it results in a higher optical and image producing efficiency of such camera as will now be explained.

35 *Disadvantages of the swing back.*—If the sensitized plate 501, Fig. 7, is mounted to turn in the camera box 500 on a horizontal axis P, the camera is virtually provided with what is known as a "swing back." The swing back serves mainly to turn the plate 40 501 back into the vertical position 503 to avoid distortion whenever the camera cannot take in the whole of the object to be photographed without being pointed downwardly as shown in Fig. 7, or upwardly as 45 would be the case in Fig. 7 reversed.

If M were a glass lens its nodal plane MT' would be met in T' by the vertical plane of the object 502 to be photographed; and, in accordance with equation 3 and Fig. 4, the 50 camera plate 501 to be in focus at all points should be turned clockwise to fall in with line PT. With the plate 501 in its normal or full line position the operator, therefore, has two alternatives; he may, first, tilt the 55 upper edge of the plate slightly toward the object to improve focus, and he may, secondly, tilt the plate back away from the object to improve the perspective outline. He, therefore, secures better perspective by 60 wholly sacrificing sharpness and he can then only recover a passable sharpness by reducing lens aperture and the speed of the lens.

In current practice the object 502 to be

photographed is at least five times farther 65 from the camera than shown in Fig. 7, so that the forward tilt VPT to improve focus becomes negligible, and the plate in its normal full line position 501 practically yields the sharpest and brightest obtainable image. 70 True, this image is distorted with its verticals converging in V, but the distortion is easily cured in my tilting enlarger because the detail has been sharply recorded. Any person having my enlarging camera, Fig. 1 75 or Fig. 3, with tilting gear to cure distortion will, therefore, preferably use the camera of Fig. 7 with its plate in the normal full line position 501.

75 *Disadvantages of the rising front.*—If the lens M'', Fig. 9, be mounted in a board 516 that slides vertically across the front end of the camera box 515, while the sensitized plate 517 remains normal and vertical, the camera is provided with what is known as a "rising 80 front," which is used for the same purposes as the "swing back." In Fig. 9 it is shown dropped as it would have to be if the camera of Fig. 9 were substituted in Fig. 7 to produce the same correct perspective qPr. 85 90 That is to say, points M''q''P'' and r'' of Fig. 9 are exactly superposable with the corresponding points M, q, P and r of Fig. 7.

If M'' of Fig. 9 were a glass lens, its principal axis would meet the plate 517 near the 95 lower edge, at m, showing that normally discarded and poorly acting marginal rays, such as M''q'', are brought into use and that the many highly desirable rays which pass just below center m are discarded. Here 100 again, as with the swing back, passable sharpness can only be secured by reducing the effective aperture and speed of the lens.

105 *Rising front and tilt back combined.*—It is seen that the rising front, Fig. 9, shifts a valuable part of the lens field off the sensitized plate 517 to bring into use poorly acting and usually discarded marginal rays; that the tilt back inclines the plate 503, Fig. 7, on the lens axis MP so that only one horizontal line of the plate can be sharply focused at a time; that these different disadvantages of rising front and swing back are not mutually compensated by the combined use of rising front and tilt back; finally, that both rising front and tilt back involve the use of levels, of reduced lens aperture and of prolonged exposure only to produce 110 negatives that are not as uniformly sharp as they might be. It is, therefore, better, on the whole, to make cameras with a solidly mounted lens, without swing back, without rising front, and without levels, to be aimed, like a gun, directly at the object to be photographed, and producing distorted but uniformly sharp and quickly exposed negatives, 115 which are easily corrected in my tilting copier or enlarger. 120 125

General remarks.

5 Note 1: The invention works best with aplanatic flat field lenses, but it will also work to produce the best available results with the common lenses having a curved field and other defects, provided these lenses be used, as they generally are, so as to give the best average definition over the whole field.

10 Note 2: In Fig. 1 and in Fig. 3 I have shown the tilting lever as pivoted on its fulcrum pin *c*, but, if preferred, it might in either of these figures, as in Fig. 10, be pivoted on one of the wrist pins instead and have sliding connections with the fulcrum as well as with the other pin.

15 Note 3: Where the inclinations of the end frames are small, as in correcting slight perspective distortions, the "sine tilt" of Figs. 3 and 10 is in all cases nearly as accurate as the "tangent tilt" of Fig. 1, because the sine and the tangent of a small angle are substantially identical.

20 Note 4: A given "sine tilt" will produce inclinations of the image frame as large as half a right angle that are substantially correct when the camera is set to copy at a certain scale *n* equal *n''*; but that are excessive or deficient accordingly as the camera copies at scales *n* that are respectively greater or less than *n''*; the value of *n''* being given by the sufficiently accurate empirical formula

$$35 n'' = \left(1 + 0.7 \frac{Pp}{f} \right) \quad (13)$$

Thus in Fig. 3, where Pp/f is 0.7, the copying factor *n''* of best performance must be $(1 + 0.7 \times 0.7)$, or 1.49. That is to say, when the camera of Fig. 3 is set as in such figure to copy one and one-half times actual size, the end frames are tilted substantially as required by theory even for inclinations 45 of the image frame as large as 45 degrees; but where the copying factor *n* is 3 the inclination of the image frame, if large, is excessive; and where the copying factor *n* is 1 the inclination of the image frame, if 50 large, is too small. An instance of such deficient inclination is shown in Fig. 10, where the tilting gear is substantially the same as in Fig. 3, but the camera is set for copying factor *n* equal 1.2 or $6/5$. In all cases, 55 therefore, where the contemplated range of variations in the values of the copying factor *n* and of the end frame inclinations *a* and *a'* is large it is preferable to use a tangent tilt, such as that of Fig. 1. The substitution of a "tangent tilt" for the "sine tilt" in either Fig. 3 or Fig. 10 presents 60 no mechanical difficulties.

Note 5: If the lens is specially designed for the exclusive use of a certain group of

actinic rays, or if it has a so-called "chemical focus," all adjustments of the focusing mechanism should be made for such actinic or chemical rays, as will readily be understood.

65 Note 6: A mathematical equivalent of my 70 equation 3 is found in the formula

$$\tan. a' = \frac{FN}{PN - FN} \times \tan. a \quad (14)$$

75 which was published by Captain Scheimpflug in the "Photographische Correspondenz," Vienna, 1898 (p. 118, Fig. 5 on page 119, and *erratum* on p. 221).

A mathematical equivalent of my equations 3 and 5 is found in the formula 80

$$\tan. a' = n \tan. a \quad (15)$$

85 which was published by Captain de Romance in the "Bulletin de la Société, Française de Photographie," Paris, January 15, 1899, pp. 55 to 64. The exact form of my equation 3, however, and of the "theorem" founded thereon is novel and important, because it brings out and renders patent the 90 elements *NP* and *N'P'* which I directly utilize as the automatically varying lever arms of my tilt lever.

What I claim as my invention and desire 95 to secure by Letters Patent is:

1. The combination with an enlarging or copying camera comprising a lens frame, and two end frames mounted to rotate on parallel axes; of arms rigidly connected with said three frames, and a lever adapted 100 to act on said arms to revolve the said end frames simultaneously in opposite directions.

2. The combination with a copying or enlarging camera comprising a lens frame and two end frames mounted to rotate on axes that are parallel and adjustable to vary their distances from the nodal or principal planes of the lens; of mechanism connecting said end frames and adapted to cause them 110 to revolve simultaneously in opposite directions.

3. The combination with a copying or enlarging camera comprising a lens frame and two end frames respectively mounted to rotate on parallel axes of their focal planes, such axes being adjustable in position to permit of setting them in different conjugate relations to the lens for securing an axial image on the one axis bearing different 115 desired proportions to the axial original on the other axis; of mechanism connecting said end frames and adapted to cause them to revolve in opposite directions.

4. The combination with an enlarging or 125 copying camera comprising a lens frame, and two end frames mounted to rotate on parallel axes, of a lever having its fulcrum

on the said lens frame and adapted to act with its ends on the two end frames to revolve them in opposite directions.

5. The combination with an enlarging or copying camera comprising a lens frame, and two end frames mounted to rotate on parallel axes, of a lever having its fulcrum adjustably mounted on the said lens frame and adapted to act with its ends on the 10 two end frames to revolve them in opposite directions.

6. The combination with an enlarging or copying camera comprising a lens frame, and two end frames mounted to rotate on parallel axes, of automatic focusing gear 15 to change the copying factor or size of the image; and tilting mechanism to change the shape of the image, said tilting mechanism being adapted to permit the free action of 20 the focusing gear.

7. The combination with an enlarging or copying camera having a lens frame, and two end frames mounted to rotate on parallel axes, of automatic focusing gear to 25 change the copying factor or size of the image; and tilting mechanism to change the shape of the image, said tilting mechanism having pin and slot engagement with two of the said frames to provide for automatically 30 changing the velocity ratio of transmission as required when changes are made in the said copying factor by operation of the said focusing gear.

8. The combination with an enlarging or copying camera having a lens frame, and two end frames mounted to rotate on parallel axes, of automatic focusing gear to change the copying factor or size of the image; and tilting mechanism to change the shape 40 of the image, said tilting mechanism having pin and slot engagement with the two end frames to provide for automatically changing the velocity ratio of transmission as required when changes are made in the said copying factor by operation of the said focusing gear.

9. The combination with an enlarging or copying camera comprising a lens frame, and two end frames mounted to rotate on parallel axes of their respective focal planes; of a support for the lens frame and supports for the pivotal axes of the said end frames, one of said end frames having an arm extending perpendicularly from its 50 axis and focal plane toward the lens; and the other end frame having a similar perpendicular arm extending away from the lens; and a lever adapted to mechanically connect substantially corresponding points 55 of the said two perpendicular arms; the fulcrum of said lever being mounted on the said lens frame at a point which divides said connecting lever into effective lever arms substantially equal to the correspond-

ing distances of the nodal points of the lens 65 from the said pivotal axes.

10. The combination with an enlarging or copying camera comprising a lens frame, and two end frames mounted to rotate on parallel axes of their respective focal planes; 70 of a support for the lens frame and supports for the pivotal axes of the said end frames, said three supports being adjustable to vary the copying factor as measured on said pivotal axes; one of said end frames 75 having an arm extending perpendicularly from its axis and focal plane toward the lens; and the other end frame having a similar perpendicular arm extending away from the lens; and a lever adapted to mechanically connect substantially corresponding 80 points of the said two perpendicular arms; the fulcrum of said lever being mounted on the said lens frame at a point which divides said connecting lever into effective 85 lever arms substantially equal to the corresponding distances of the nodal points of the lens from the said pivotal axes.

11. The combination with a copying or enlarging camera, having its two end frames 90 mounted to turn on parallel diametral axes P, P' perpendicular to and intersecting the principal axis F, F' of the lens mounted in the lens frame; of end frame tilting mechanism comprising two substantially equal 95 crank arms extending perpendicularly and in the same direction away from the said two end frames respectively, and a tilt lever adapted to act on the two movable ends of such crank arms to tilt the said two end frames in opposite directions, said tilt lever having its fulcrum mounted on the said lens frame.

12. The combination with a copying or enlarging camera, having its two end frames 105 mounted to turn on parallel diametral axes P, P' perpendicular to and intersecting the principal axis F, F' of the lens mounted in the lens frame; of end frame tilting mechanism comprising two substantially equal 110 crank arms extending perpendicularly and in the same direction away from the said two end frames respectively, and a tilt lever adapted to act on the two movable ends of such crank arms to tilt the said two end frames in opposite directions, said tilt lever having its fulcrum mounted on the said lens frame; also means to permit of varying the conjugate focal distances $PN, P'N'$ of the axes P, P' from the nodal points N, N' of 115 the lens, and means for automatically varying the two lever arms of the tilt lever to keep them substantially equal to the said varying conjugate distances $PN, P'N'$, respectively.

13. The combination with a copying or enlarging camera, having its two end frames mounted to turn on parallel diametral axes 125

P, P' perpendicular to and intersecting the principal axis F, F' of the lens mounted in the lens frame; of end frame tilting mechanism comprising two substantially equal 5 crank arms extending perpendicularly and in the same direction away from the said two end frames respectively, and a tilt lever adapted to act on the two movable ends of such crank arms to tilt the said two end 10 frames in opposite directions, said tilt lever having its fulcrum mounted on the said lens frame; also means to permit of varying the conjugate focal distances PN, P'N' of the axes P, P' from the nodal points N, N' of 15 the lens, and means for automatically varying the two lever arms of the tilt lever to keep them substantially equal to the said varying conjugate distances PN, P'N', respectively; and means for simultaneously 20 displacing the two diametral axes P and P' with relation to the lens in accordance with Newton's formula, or equations 1 and 2.

14. The combination with a copying or enlarging camera comprising a lens frame, 25 and two end frames respectively mounted to rotate on diametral axes of their image planes, such axes being parallel and adjustable to vary their distances from the nodal points of the lens; of mechanism connecting said end frames and adapted to cause their image planes to revolve simultaneously in opposite directions from the positions they occupy when parallel or set perpendicularly to the lens axis, at such rates, 30 for all positions of the said diametral axes, as to always meet the principal or nodal planes of the lens substantially in conjugate or directly opposite lines.

In testimony whereof, I have signed my 40 name to this specification in the presence of two subscribing witnesses.

JOSEPH BECKER.

Corrections in Letters Patent No. 1,126,352.

It is hereby certified that in Letters Patent 1,126,352, granted January 26, 1915, upon the application of Joseph Becker, of Washington, District of Columbia, for an improvement in "Copying or Enlarging Cameras," errors appear in the drawings and in the printed specification requiring correction as follows: In the drawings, Fig. 3 FOR "O" READ O'; in the specification, page 2, in the four equations included between lines 70 to 90, FOR "tan." six times occurring READ tan; page 3, in the equation included between lines 6 to 10, FOR "tan." twice occurring READ tan; page 7, equation 12, FOR "sec." READ sec; page 9, equations 14 and 15, FOR "tan." four times occurring READ tan; page 1, line 22, FOR "meridional" READ meridional; page 2, ITALICIZE lines 91 to 96; page 9, line 77, ITALICIZE "z"; page 9, line 85, FOR ", *Française*" READ *française*; page 9, line 97, FOR "lense" READ lens; page 10, line 36, FOR "counted" READ mounted; and that the said Letters Patent should be read with these corrections therein, that the same may conform to the record of the case in the Patent Office.

Signed and sealed this 2nd day of March, A. D. 1915.

[SEAL.]

J. T. NEWTON,
Acting Commissioner of Patents.
